CLAIM

The ornamental design for a control enhancing handle
for emery boards, as shown and described.

DESCRIPTION

FIG. 1 is a perspective view of a control enhancing
handle for emery boards showing my new design;
FIG. 2 is a top plan view thereof, the side opposite
being identical to the side shown;

FIG. 3 is a right side elevational view thereof;
FIG. 4 is a left side elevational view thereof; and
FIG. 5 is a front end elevational view thereof, the side
opposite being a mirror image of the side shown.

The broken line showing of an emery board in FIGS. 2
and 3 is for illustrative purposes only and forms no part
of the claimed design.
